FOREIGN PATENT DOCUMENTS

CH 670746 4/1989
(Continued)*Primary Examiner* — Holly Bayham(74) *Attorney, Agent, or Firm* — Griffiths & Seaton PLLC(57) **CLAIM**

The ornamental design for a financial transaction card with storage chamber, as shown and described.

DESCRIPTION

FIG. 1 is a front, perspective view of a financial transaction card with storage chamber showing our new design;

FIG. 2 is a rear, perspective view thereof;

FIG. 3 is a front view thereof;

FIG. 4 is a rear view thereof;

FIG. 5 is a right side view thereof, the left side view being a mirror image thereof;

FIG. 6 is a top view thereof; and,

FIG. 7 is a bottom view thereof.

The broken lines showing stitching and a fastening tab are for the purposes of illustrating environment and form no part of the claimed design.
